UNITED STATES PATENT OFFICE.

GEORGE A. BOYDEN, OF BALTIMORE, MARYLAND, ASSIGNOR OF ONE-HALF
TO CHARLES B. MANN, OF SAME PLACE.

FLUID-PRESSURE CAR-BRAKE.

SPECIFICATION forming part of Letters Patent No. 356,025, dated January 11, 1887.

Application filed April 12, 1886. Serial No. 198,545. (No model.)

To all whom it may concern:

Be it known that I, GEORGE A. BOYDEN, a citizen of the United States, residing at Baltimore, in the State of Maryland, have invented 5 certain new and useful Improvements in Fluid-Pressure Car-Brakes, of which the following is a specification, reference being had therein to the accompanying drawings.

My invention relates to improved means for 10 operating car-brakes by fluid-pressure, and has for its object to provide for freight-trains a power-brake in which the agent for communicating the power shall be fluid under pressure; and the invention especially contemplates 15 that the engineer may at all times and under all conditions of running operate and control the brakes of all cars equipped according to this invention.

In the drawings which illustrate the invention, Figure 1 is a side view of a train equipped 20 with the improved brake. Fig. 2 is a top view of a train in which the trucks and brake mechanism of one car are shown without the car-body. Fig. 3 is a view showing the principal 25 parts comprised in this invention detached from the train. As shown in this view, oil, water, or other liquid is designed to be used in the improved train-pipe, and the desired pressure on the liquid is obtained by a pipe 30 directly connecting the steam-space of the locomotive-boiler with a tank containing the said liquid. Fig. 4 is a view showing the principal parts comprised in this invention detached 35 from the train. As here shown, oil, water, or other liquid is designed to be used in the improved train-pipe, and the desired pressure on the liquid is obtained by an ordinary compressed-air apparatus. Fig. 5 is a view of the principal parts comprised in this 40 invention detached from the train, the improved train-pipe in this instance being shown detached from the "grippers" which actuate the brake mechanism on the car. As here shown, compressed air is designed to be used 45 in the improved train-pipe, an ordinary air-compressing apparatus being employed. Figs. 6 and 7 are end perspective views showing the collapsible train-pipe and the gripper for the same. One view illustrates the train-pipe expanded 50 and the other collapsed. Figs. 8 and 9 are top views of the train-pipe and gripper.

Fig. 10 shows a modification. Instead of the train-pipe having the collapsible and expandible feature continuous from end to end, there may be employed an iron pipe on each car, having sections or portions of collapsible hose for co-operation with a gripper. 55

Referring to the drawings, the letter A designates an ordinary freight-car; B, the trucks of the car, equipped with ordinary brake mechanism, which includes shoes, brake beams and lever, and arranged, as usual, to be operated by the well-known hand-wheel, C, on an upright shaft. With this ordinary brake mechanism I connect a train-pipe or hose-gripper, d, which 60 may be made in any suitable way.

The drawings show one form of construction for the gripper, comprising two jaws, d d', one of which is fixed stationary and the other movable, its movement being toward and away 65 from the other. The movable jaw is attached to a rod, e, which is supported in bearings f below the car-body, and extends crosswise thereof. This rod has endwise movement in its bearings. A pulley, g, is mounted on the 70 said rod, and two other pulleys, h, are fixed immovably and in any suitable way to the car-body, one of the said two fixed pulleys being at each side of the rod e. A chain, i, passes on one side of the rod-pulley g, and on the opposite side of the two fixed pulleys h, and connects with a brake-lever, k, on the trucks. 75

It will be understood from this description that the rod e by moving endwise will cause a pull on the chain i, and thereupon the brake- 80 shoes n will be applied to the wheels. 85

I employ a collapsible and expandible train-pipe, L, to contain fluid under pressure, and the said pipe is placed in the gripper, (that is, between the two jaws d d'), or a device of 90 equivalent character.

The train-pipe L is continuous from a source of supply of fluid under pressure, located on the tender or locomotive, along all the cars composing the train, or along as many of said 95 cars as may be desired.

The term "train-pipe" as here used is the direct continuous pipe through which the fluid (whatever it may be—water, oil, steam, or air) passes from the source of supply of 100 fluid-pressure along the cars of the train. It does not include branch pipes, chambers,

or cylinders, which parts have heretofore been used on the cars, but are not employed in my brake.

My collapsible and expandible train-pipe 5 embraces that pipe only through which the fluid will pass that is to operate the brakes of those cars along which said train-pipe extends.

The forward end of the train-pipe, when in 10 use, is connected with the tank O, (which represents the source of a supply of fluid under pressure,) and the other end, p, is closed or sealed. As here shown, the train-pipe differs 15 from that of other fluid-pressure brakes, in that throughout its entire length it is sealed or closed, or, in other words, it is without openings or branch connections, and this comprises one feature of my invention. This improved train-pipe operates the car-brakes by 20 its action when collapsing or expanding, which feature is illustrated in Figs. 6, 7, 8, and 9 of the drawings.

In Figs. 6 and 8 the train-pipe L is shown expanded. The expansion is produced by the 25 fluid-pressure, the fluid being in and throughout the train-pipe. The result of the expansion is to spread the jaws d d' of the gripper, or whatever equivalent device may be used, and thereby move the rod e, and through the 30 connections between it and the brake-lever h operate the brakes—that is, either to apply them or to hold them off.

In Figs. 7 and 9 the train-pipe L is shown collapsed. This condition is produced by a 35 withdrawal of the fluid-pressure from the train-pipe. When the train-pipe is thus collapsed, the jaws d d' of the gripper are nearer together—that is, the movable jaw approaches the stationary one—and the rod e and connections are moved in the opposite direction. 40 This collapsing and expanding of the train-pipe comprises another feature of my invention.

It will be obvious that the collapsible and 45 expandible action of the train-pipe may be utilized either to apply the brakes by the direct action of the expanded pipe and release them by collapsing the pipe, or, reversely, the expansion may serve to hold the brakes off, 50 and any well-known means (such, for instance, as a spring acting in connection with the brake mechanism) employed to apply the brakes.

The collapsible and expandible train-pipe 55 may be employed in controlling car-brakes by either the hydraulic or pneumatic plan—that is, the train-pipe may receive water, oil, spirit, glycerine, or any compound or admixture of these; also, steam may be used and air.

The drawings herewith illustrate three plans, 60 which will now be described.

The tank O in Figs. 1, 2, and 3 is for oil, water, or other liquid which is to enter the train-pipe. A pipe, q, connects the top of this tank with the steam-boiler R of the locomotive. Thereby the pressure of the steam in the 65 boiler is exerted on the liquid in the tank. The train-pipe L is connected with the liquid-tank

O. A three-way cock, s, in the said connecting-pipe controls the passage of the steam to the liquid-tank, and the exhaust-pipe t, connected with the cock, provides for the release of the pressure. By this well-known device the engineer will have control of the brakes, and may at any time apply or release them.

In Fig. 4 the tank O is also for oil, water, 75 or other liquid. In this instance the pipe q connects with a tank, R', of compressed air. Thereby the pressure of the air in the tank R' is exerted on the liquid in the tank O. A steam-cylinder, U, and a condensing-pump, V, 80 of the usual construction, are employed to compress the air. The three-way cock s controls the passage of the air to the liquid-tank, and the operation otherwise is the same as when steam is used.

Fig. 5 illustrates a plan for the use of compressed air in the collapsible and expandible train-pipe. In this instance no liquid is used. The tank O is for the compressed air, and the pipe w connects this tank directly with the 90 train-pipe L. The three-way cock s, exhaust-pipe t, cylinder U, and pump V are all arranged as usual.

The train-pipe having the features of this invention may consist of suitable hose, 95 commencing at the tank O and continuing from thence along the cars of the train, and may be in sections of suitable length coupled together, as at x; or, as shown in Fig. 10, each car may be provided with iron pipe L', secured to the 100 car by suitable fastenings, y, like the train-pipe of the well-known air-brake, and short sections of collapsible and expandible hose L connected with said iron pipe. In this case the usual hose-couplings, z, between cars 105 would be necessary. The gripper d, or other equivalent device, will then co-operate with the said short section of hose, as hereinbefore described. Therefore where I claim a collapsible and expandible train-pipe said claim includes 110 a continuous hose of this character or a pipe composed in part of metal and in part of hose, either or both.

It is obvious the device herein termed a "gripper" 115 may be otherwise constructed, and it is also plain that the mechanism which connects the collapsible and expandible train-pipe with the ordinary brake-shoes may be constructed and arranged in a variety of ways besides that here shown. My invention consisting of the 120 collapsible and expandible train-pipe is not, therefore, limited or affected by any such changes.

In case liquid is used in the train-pipe, the closed end should be provided with a cock, j, 125 whereby to empty the pipe of air when it is desired to fill it with liquid; or when the pipe is full of liquid the same may be drawn off.

No claim is herein made to a detachable or removable train-pipe, claims thereto being 130 embraced in my application for patent filed June 15, 1886, Serial No. 205,190. No claim is made to a gripper separately, nor to the mechanism separately, which connects the col-

lapsible and expansible train-pipe with the ordinary brake mechanism on the car-truck, claims to said parts being embraced in my application for patent filed June 22, 1886, No. 5 205,865.

Having described my invention, I claim and desire to secure by Letters Patent of the United States—

1. A railway-car brake having, in combination, a source of supply of fluid-pressure, brake mechanism on the cars, and a collapsible and expansible train-pipe having one end connected with said source of supply and the other end closed and throughout its length sealed, 15 or, in other words, without openings or branch connections, as set forth.

2. In a railway-car brake, a collapsible and expansible train-pipe, in combination with a source of supply of fluid-pressure and brake 20 mechanism on the cars which is actuated by the collapsing and expanding of said pipe, as set forth.

3. A railway-car brake having, in combination, a source of supply of fluid-pressure, brake mechanism on the cars, a collapsible and expansible train-pipe having one end connected with said source of supply, and a gripper capable of holding the said train-pipe and connected with the said brake mechanism, as set forth. 25

4. In a railway-car brake the mechanism of which is operated by fluid-pressure, the combination therewith of a collapsible and expansible train-pipe which is closed at one end and sealed throughout its length, as set forth. 30 35

In testimony whereof I affix my signature in presence of two witnesses.

GEORGE A. BOYDEN.
